US0D1015850S

(12) **United States Design Patent** (10) Patent No.: **US D1,015,850 S**
(45) Date of Patent: ** Feb. 27, 2024

(54) **COT FASTENER**

(71) Applicant: **Ferno-Washington, Inc.**, Wilmington, OH (US)

(72) Inventors: **Nicholas V. Valentino**, Springboro, OH (US); **Timothy R. Wells**, Hillsboro, OH (US); **Christopher Way**, Mason, OH (US); **Alan Raymond Cambridge**, Wooloowin (AU); **Gavin Lee Broadley**, Maroochla (AU)

(73) Assignee: **Ferno-Washington, Inc.**, Wilmington, OH (US)

(**) Term: **15 Years**

(21) Appl. No.: **29/843,059**

(22) Filed: **Jun. 17, 2022**

Related U.S. Application Data

(60) Continuation of application No. 16/746,085, filed on Jan. 17, 2020, now Pat. No. 11,458,050, which is a division of application No. 15/504,154, filed on Feb. 15, 2017, now Pat. No. 10,568,787, and a continuation-in-part of application No. PCT/US2015/054832, filed on Aug. 19, 2015.

(57) **CLAIM**

The ornamental design for a cot fastener, as shown and described.

DESCRIPTION

FIG. 1 is a perspective view of a cot fastener;

FIG. 2 is an enlarged front elevation view thereof;

FIG. 3 is a left side elevation view thereof;

FIG. 4 is an enlarged rear elevation view thereof;

FIG. 5 is a right side elevation view thereof;

FIG. 6 is a top plan view thereof; and,

FIG. 7 is a bottom plan view thereof.

The broken lines depict portions of the cot fastener that form no part of the claimed design.
